UNITED STATES PATENT OFFICE

96,451

DESIGN FOR A POWER UNIT

Thomas C. Delaval-Crow, Bristol, Conn., assignor
to General Motors Corporation, Detroit, Mich.,
a corporation of Delaware

Application May 18, 1935, Serial No. 56,894

Term of patent 14 years

To all whom it may concern:

Be it known that I, Thomas C. Delaval-Crow, a citizen of the United States, residing at Bristol, county of Hartford, State of Connecticut, have invented a new, original, and ornamental Design for a Power Unit, of which the following is a specification, reference being had to the accompanying drawings, forming part hereof.

Fig. 1 is a perspective view of a power unit showing my design.

Fig. 2 is a perspective view of the power unit from another angle, and

Fig. 3 is a perspective view of the power unit from still another angle and viewed from the motor end.

I claim:

The ornamental design for a power unit substantially as shown.

In testimony whereof I hereunto affix my signature.

THOMAS C. DELAVAL-CROW.
